GLOVE

Carl F. Schuessler, Chicago, Ill.

Application January 17, 1942, Serial No. 427,150

10 Claims. (Cl. 66—174)

This invention relates to a glove and more particularly to a knitted glove.

One difficulty with knitted gloves is the tendency of the inner finger and thumb portion of the glove to wear by reason of frequent contact with wearing surfaces. Further, because of the loose knitting, there is a tendency for key rings and other articles to catch within the stitches and to tear the glove. On the other hand, if the glove is knitted rather tightly, then the fingers and thumb cannot be manipulated with ease and the glove is unsatisfactory.

An object of this invention is to provide a glove wherein the fingers and thumb can be readily moved without effort while at the same time providing an extremely sturdy and compact inner surface which will resist wear and which will also prevent articles, etc. from catching within the stitches. A further object is to provide a method whereby the thumb can be readily knit without requiring fashioning operations. Yet another object is to provide a glove having a sturdy inner portion of compact formation while allowing great flexibility for the fingers and thumb, and also providing a structure wherein the added finger and thumb portions can be united integrally with the glove body with a minimum of effort. Other specific objects and advantages will appear as the specification proceeds.

The invention is illustrated in a preferred embodiment by the accompanying drawing, in which—

Figure 1 is a plan view of the face of a glove embodying my invention; Fig. 2, a plan view of the top or back of the glove; Fig. 3, a detail sectional view, the section being taken as indicated at line 3 of Fig. 1; Fig. 4, a plan view of a tubular knitted strip from which thumb portions may be formed, the stitches being more tightly formed on the side shown; and Fig. 5, a broken plan view of the opposite side of the strip illustrated in Fig. 4, the stitches being uniformly larger on the side shown.

I have found that an extremely satisfactory glove can be formed, overcoming the disadvantages hereinbefore mentioned, by knitting the fingers and thumbs so as to provide tight or close stitches on the inner side thereof while leaving regular or large stitches on the outer finger and thumb portion. By this means, a compact and sturdy inner surface is provided which will stand wear and which will prevent articles from catching within the stitches, while at the same time the desired flexibility is afforded by the regular

or large stitches on the outer surface of the finger or thumb portion. In other words, the flexing of the joints is accommodated by the outer wall of regular or large stitches, while the inner wall of substantially tight stitches provides a surface which is not knitted for flexing but which gives the compact formation needed for withstanding wear and other purposes mentioned.

- 10 In the illustration given, A designates a glove having a wrist portion 10 and a body portion 11. The body of the glove and wrist as described may be formed on a flat knitting machine and the ends united by a seam or, if desired, the glove 15 may be formed by a tubular machine. After forming the body of the glove as described, the finger portions may be united by stitching, and similarly the thumb portion may be secured in the position shown after a stitch has been cut to form the opening in the body.
- 20 In the illustration given, 12 indicates the thumb portion secured to the body 11. The thumb is preferably formed from a tubular knitted strip, indicated by the numeral 13 in Figs. 4 and 5.
- 25 The fingers of the glove are indicated by the numeral 14 and are also preferably formed from tubular knitted lengths which are severed at certain distances.
- 30 In the forming of the knitted tubular strip 13, as shown in Figs. 4 and 5, the strip is knitted with regular or large stitches, as indicated by the numeral 15, along the back of the thumb, while on the inner face of the thumb the stitches are tight or small, as indicated by the numeral 16. At spaced intervals, a row or a plurality of rows of regular or large stitches 15 are formed between the tight stitching on the face portion of the strip, as indicated more clearly in Fig. 4. In other words, the knitted tubular strip, shown 35 in Fig. 4, has on the outer portion thereof, regular stitches 15 while on the inner face the stitches are tight or small stitches, as indicated by the numeral 16, but the tight stitches 16 are spaced at regular intervals by rows of regular stitches 15. In the particular illustration given, there are 40 six rows of loose stitches formed between the rows of close or tight stitches.
- 45 When the thumb is formed from the strip shown in Fig. 4, the severance is made on the inner side of the row of regular stitches; that is, just to the right of the angular stitches, as shown in Fig. 4. The outer end of the thumb is then closed by stitching, and the closed thumb is then secured to the body 11 of the glove by looping or joining the lowermost portion thereof to the ad-

5 adjacent stitches of the body. This is a well-known operation and need not be described in detail. By employing the six rows of loose or regular stitches, as described, there is a looseness about the lower portion of the thumb, causing it to flare somewhat at the base, as indicated at 17 in Fig. 1. Ordinarily, it is necessary to fashion the lower portion of the thumb by a special knitting operation which causes the thumb portion to broaden out at its base. By the operation described, this 10 fashioning step can be omitted because the use of the loose stitches at the base of the thumb, all the way around, produces sufficient fullness to cause a flaring or widening of the thumb at this point.

15 Similarly, in the forming of the fingers 14, I prefer to leave a row of loose or regular stitches 18, as indicated in Fig. 1, to facilitate the securing of the finger to the glove body. In the forming of the tubular strip, the row 18 of regular stitches serves as a marker to indicate where severance should take place, and then the loose stitches greatly aid the operator in the looping or joining operation. Instead of the single row of 20 stitches 18, several rows of loose stitches may be used. The row or rows of loose stitches increase 25 the flexibility of the fingers at their point of junction with the body of the glove.

If desired, the bottom and inner portion of the 30 glove may be provided with tight stitches in contrast with the loose stitches along the back or outer portion of the glove. Whether or not tight stitches are employed on the inner face of the glove body, it is important that tight stitches be employed on the inner face of the fingers and also of the thumb, because at these points the major part of the wear occurs and at these points there is the possibility of key rings and the like catching and pulling stitches.

Any suitable means for forming the tighter 35 stitches at one point rather than at another, may be employed. In my Patent No. 2,150,730, of March 14, 1939, I have set forth a description of mechanism suitable for forming in a single operation tight and loose stitching. Longer and shorter needles may be placed in tubular knitting machines, etc. for forming tight stitches at one point, while loose stitches are formed at another point in the same row of stitches. The tight and loose or regular stitches can also be made by using a device which tightens or loosens cams at desired intervals. Since this mechanism is well known, no detailed description need here be given. After the mechanism is adjusted for operation, long strips of tubular knitting with regular or loose stitches on the outer side thereof and close or tight stitches on the inner side thereof may be formed expeditiously, and the tight or close stitches may be separated by one or, if desired, a number of rows of loose stitches.

The new glove, by reason of the tight stitching on the inner sides thereof, tends to form a curve which fits the normal curvature of the hand; that is, the fingers tend to curve inwardly as a result of the influence of the tight stitches, and the curvature thus produced is substantially that of the natural curvature of the hand. The loose or regular stitches on the outer side of the fingers and thumb provide the looseness that is necessary for freedom of movement and flexibility, while at the same time there is provided on the inner sides a compact and tightly knitted body which will resist wear over long periods and which does not enable stitches to be readily pulled or torn. In the glove-forming operation,

5 the operator can quickly sever the strips at the desired points by the spacing rows of loose stitches between the rows of tight or close stitches, no measuring instrument being required, and the loose stitches provided at the lower ends of the thumb and finger portions enable a quick joining of the parts to form a complete glove.

10 While the thumb is shown provided with six rows of relatively loose stitches at its base, any desired number of rows may be used. The number required for enlarging the thumb base will vary with different sizes and types of gloves.

15 While in the foregoing specification, I have set forth certain details as descriptive of the one mode of carrying out the invention, it will be understood that such details may be widely varied by those skilled in the art without departing from the spirit of my invention.

I claim:

1. A knitted glove of the character set forth, having its front side provided with an area of close stitches and having the portion of its back side aligned with said area of close stitches provided with a flexing area of relatively loose 20 stitches.

2. A knitted glove of the character set forth, having its front side provided with an area of close stitches adapted to withstand wear and having the portion of its back side aligned with said area of close stitches formed of relatively loose 25 stitches.

3. A knitted glove having a body portion and finger and thumb portions, said finger portions being provided on their front sides with areas of close stitches and having their back sides formed of relatively loose 30 stitches.

4. A knitted glove having a body portion and finger and thumb portions, said thumb portion at least having its inner side provided with an area of relatively close stitches and having its back side formed of relatively loose 35 stitches.

5. A knitted glove consisting of a body portion and finger and thumb portions, said finger and thumb portions having their front sides provided with areas of relatively close stitches and having their back sides formed of relatively loose 40 stitches.

6. A knitted glove of the character set forth, having its front side provided with areas of 45 relatively close stitches and its back side formed of relatively loose stitches whereby said glove is caused to assume a curvature substantially conforming to the normal curvature of the hand.

7. A knitted glove consisting of a body portion and finger and thumb portions, at least one 50 of said fingers having an area of relatively tight stitches in the front thereof and having loose stitches in the back portion thereof, said finger having at least one row of relatively loose stitches encircling the base thereof whereby said finger is joined to the body of the glove.

8. A knitted glove consisting of a body portion and finger and thumb portions, said finger portions having areas of relatively close stitches in the front thereof and loose stitches in the back thereof, said finger portions being joined to said glove body with at least one row of loose 55 stitches extending about the front and back of said finger portion and at the base thereof.

9. A knitted glove consisting of a body portion and finger and thumb portions, said thumb portion having on its front side an area of relatively close stitches and on its back side an area of relatively loose stitches, said thumb portion having at its base a plurality of rows of 60

tively loose stitches, and means connecting the lowermost of said rows of loose stitches to said glove body.

10. A knitted glove consisting of a body, thumb and finger portions, said glove body having an enlarged opening about which the thumb portion is to be secured to said body, and said thumb portion having on its front an area of close

stitches and at its rear an area of loose stitches, said thumb portion having also at its base a plurality of complete rows of loose stitches permitting an enlargement in the contour of the thumb base, the lowermost of said loose stitches being secured to said glove body.

CARL F. SCHUESSLER.
